BOXING ROUND TALLY

August G. Reibling, Edgewood, R. I., assignor to Lloyd Plastics and Mold Co., Warwick, R. I., a corporation of Rhode Island

Application June 26, 1957, Serial No. 46,754

Term of patent 14 years

(Cl. D34—5)

FIG. 1

FIG. 2

FIG. 3

I claim:

The ornamental design for a boxing round tally, as shown.
